VESSEL PROPELLING AND STEERING
MECHANISM

Andrew F. O'Bannon, Los Angeles, Calif.

Application December 17, 1947, Serial No. 792,149

2 Claims. (Cl. 115—29)

1

This invention relates to new and useful improvements and structural refinements in vessel propelling and steering mechanisms, more specifically, mechanisms of this type such as may be conveniently and effectively employed on boats, ships, and the like, and the principal object of the invention is to provide a device of the character herein described, wherein the conventional propeller screw is substituted by an oscillating and undulating blade, whereby more efficient utilization of the source of motive power is realized.

A further object of the invention is to provide a mechanism of the type described wherein a plurality of propelling members may be employed in multiple and wherein, by partially rotating the entire propelling unit about a vertical axis, convenient and effective steering of the associated vessel is effected.

Another object of the invention is to provide a vessel propelling and steering mechanism which is simple in construction, which may be easily and conveniently manipulated, and which will not easily become damaged.

An additional object of the invention is to provide a vessel propelling and steering mechanism which may be conveniently employed on vessels of various types and sizes, which will readily lend itself to economical manufacture, and which is otherwise well adapted for the purpose for which it is intended.

With the above more important objects in view, and such other objects as may become apparent as this specification proceeds, the invention consists essentially of the arrangement and construction of parts as illustrated in the accompanying drawings, in which:

Figure 1 is a side elevational view of the invention, the same being taken substantially in the plane of the line 1—1 in Figure 4 and being shown in association with a vessel illustrated in cross section;

Figure 2 is a cross sectional view, taken substantially in the plane of the line 2—2 in Figure 1 and showing the mechanism at standstill;

Figure 3 is a cross sectional view, taken substantially in the plane of the line 3—3 in Figure 1;

Figure 4 is a cross sectional view, taken substantially in the plane of the line 4—4 in Figure 1; and

Figure 5 is a cross sectional view, similar to that shown in Figure 2, but illustrating the mechanism in motion.

Like characters of reference are employed to designate like parts in the specification and throughout the several views.

Referring now to the accompanying drawings in detail, the invention consists of a vessel propelling and steering mechanism designated generally by the reference character 10, the same

2

embodiment in its construction a carrier assembly or turntable 11 provided within the stern portion 12 of a vessel 13.

The carrier assembly 11 consists of a lower race portion 14, an upper race portion 15 and an annular roller unit 16 which is interposed between the two racers 14, 15 as will be clearly apparent. The race portion 14 is stationary, being rigidly secured to or formed integrally with the hull of the vessel, and it will be noted that an arcuate slot or opening 17 extends partially around the race portion 14, as is best shown in Figure 4. The purpose of this slot will be hereinafter more fully described.

15 A power unit 18, assuming any suitable form, such as for example, an electric motor, an internal combustion engine, a steam engine, or the like, is mounted upon the upper, rotatable race 15 of the carrier 11, this power unit being operatively connected by selectively actuated drive means 20' of any conventional type to a central, vertical pivot 19 which is non-rotatably mounted at the center of the carrier. A gear 20" is secured to the pivot 19 and the gear means 20' 20 operatively moves around it when the power unit 18 is energized, whereby the race portion 15 of the carrier may be caused to rotate in either direction, as desired. This structural arrangement provides the steering mechanism, which will be hereinafter more fully described.

25 The power unit 18 also includes a laterally projecting driven shaft 20 provided with a pair of eccentrics 21, these including eccentric disks 21' and straps 21'' which are operatively connected as at 22 to suitable cranks 23 provided on a pair of vertical mounting pivots 24.

30 These pivots are rotatably journaled in suitable bearings 25 on the power unit 18 and are also rotatably journaled in the upper race portion 15 of the carrier 11. Moreover, the pivots 24 extend freely through the aforementioned slot 17 and the lower end portions of the pivots carry vertically disposed, spaced parallel propelling blades 26.

35 40 It will be noted that the pivots 24 are connected to the end portions of the blades 26 and that the blades are disposed in the vertical plane of the respective pivots, as will be clearly understood.

45 50 The blades 26 are formed from flexible, more or less resilient material and are capable of undulatory movement, as will be hereinafter described.

55 It should be understood that the power unit 18 may be controlled so as to selectively rotate the carrier 11 through the drive means 20' and impart rotation to the driven shaft 20. As has been already stated, rotation of the carrier 11 is utilized for steering purposes, whereas rotation of the shaft 20 will be transmitted through

the medium of the eccentrics 21 and the pivots 24 to produce an oscillatory movement of the blades 26. When movement of this character is imparted to the blades, the blades will become undulated as shown in Figure 5, and as a result of these undulations, forward thrust will be imparted to the vessel. It should, of course, be understood that when oscillation of the blades ceases, the blades possess sufficient resiliency to return to their normal, flat condition, as shown in Figure 2.

The blades 26 are, of course, disposed below the water line 27, and while it is appreciated that water may enter into the stern portion 12 of the vessel through the slot 17, it should be explained that the stern portion 12 merely constitutes what may be referred to as a streamlined enclosure for the propelling and steering mechanism which, as a whole, may function satisfactorily under water. Needless to say, the water is prevented from gaining access to the interior of the vessel by means of a suitable bulkhead 28 which separates the stern portion 12 from the remainder of the hull.

It should be also stated that the arrangement of the eccentrics 21 upon the shaft 20 is such as to facilitate synchronized oscillation and undulation of the blades 26, so as to prevent vibration.

In order to prevent the blades 26 from becoming entangled with under-sea weeds, and the like, a pair of deflector fins 29 are provided below the carrier 11, these fins being mounted at one end thereof on the aforementioned pivots 24, while a cross member 30 connects the mid-link portions of the fins, as will be clearly apparent. This cross member is pivotally connected to the lower end portion of the aforementioned pivot 19 such as for example, by a pivot element 30'.

The steering operation of the vessel is effected, as already explained, by energizing the power unit 18 to rotate the carrier 11, during which action the fins 29 as well as the blades 26 will be deflected to either port or starboard, as desired. It is to be noted that the provision of the arcuate slot 17 facilitates rotation of the carrier 11 while steering, that is, the slot 17 provides clearance for the pivots 24, so that the port or starboard deflection of the entire unit may be effected.

It is believed that the advantages and use of the invention will be clearly apparent from the foregoing disclosure and accordingly, further description thereof at this point is deemed unnecessary.

While in the foregoing there has been shown and described the preferred embodiment of this invention it is to be understood that minor changes in the details of construction, combination and arrangement of parts may be resorted to

without departing from the spirit and scope of the invention as claimed.

Having described the invention, what is claimed as new is:

- 5 1. Combined propelling and steering mechanism of the class described, comprising a turntable mounted in the stern of a vessel and rotatable in a horizontal plane, a pair of vertical pivot pins rotatably journaled at transversely spaced points in the peripheral portion of said turntable and projecting upwardly and downwardly therefrom, a pair of flexible propelling blades secured to and extending rearwardly from lower end portions of the respective pivot pins, a pair of cranks secured to upper end portions of the respective pins, a motor mounted on said turntable for rotation therewith and including a horizontal drive shaft extending rearwardly into the space between said pins, a pair of opposing eccentrics secured to said drive shaft and operatively connected to the respective cranks whereby said blades may be oscillated simultaneously in opposite directions, and means driven by said motor for rotating said turntable.
- 10 2. In combination with a vessel having a stern portion provided in the bottom thereof with an arcuate slot, a combined propelling and steering mechanism comprising a turntable mounted in said stern portion concentrically with said slot and rotatable in a horizontal plane, a pair of pivot pins rotatably journaled at transversely spaced points in the peripheral portion of said turntable and projecting downwardly through said slot, a pair of flexible propelling blades secured to and extending rearwardly from lower end portions of the respective pivot pins, a pair of cranks secured to upper end portions of the respective pins, a motor mounted on said turntable for rotation therewith and including a horizontal drive shaft extending rearwardly into the space between said pins, a pair of opposing eccentrics secured to said drive shaft and operatively connected to the respective cranks whereby said blades may be oscillated simultaneously in opposite directions, and means driven by said motor for rotating said turntable.
- 15 3. In combination with a vessel having a stern portion provided in the bottom thereof with an arcuate slot, a combined propelling and steering mechanism comprising a turntable mounted in said stern portion concentrically with said slot and rotatable in a horizontal plane, a pair of pivot pins rotatably journaled at transversely spaced points in the peripheral portion of said turntable and projecting downwardly through said slot, a pair of flexible propelling blades secured to and extending rearwardly from lower end portions of the respective pivot pins, a pair of cranks secured to upper end portions of the respective pins, a motor mounted on said turntable for rotation therewith and including a horizontal drive shaft extending rearwardly into the space between said pins, a pair of opposing eccentrics secured to said drive shaft and operatively connected to the respective cranks whereby said blades may be oscillated simultaneously in opposite directions, and means driven by said motor for rotating said turntable.
- 20 4. In combination with a vessel having a stern portion provided in the bottom thereof with an arcuate slot, a combined propelling and steering mechanism comprising a turntable mounted in said stern portion concentrically with said slot and rotatable in a horizontal plane, a pair of pivot pins rotatably journaled at transversely spaced points in the peripheral portion of said turntable and projecting downwardly through said slot, a pair of flexible propelling blades secured to and extending rearwardly from lower end portions of the respective pivot pins, a pair of cranks secured to upper end portions of the respective pins, a motor mounted on said turntable for rotation therewith and including a horizontal drive shaft extending rearwardly into the space between said pins, a pair of opposing eccentrics secured to said drive shaft and operatively connected to the respective cranks whereby said blades may be oscillated simultaneously in opposite directions, and means driven by said motor for rotating said turntable.
- 25 5. In combination with a vessel having a stern portion provided in the bottom thereof with an arcuate slot, a combined propelling and steering mechanism comprising a turntable mounted in said stern portion concentrically with said slot and rotatable in a horizontal plane, a pair of pivot pins rotatably journaled at transversely spaced points in the peripheral portion of said turntable and projecting downwardly through said slot, a pair of flexible propelling blades secured to and extending rearwardly from lower end portions of the respective pivot pins, a pair of cranks secured to upper end portions of the respective pins, a motor mounted on said turntable for rotation therewith and including a horizontal drive shaft extending rearwardly into the space between said pins, a pair of opposing eccentrics secured to said drive shaft and operatively connected to the respective cranks whereby said blades may be oscillated simultaneously in opposite directions, and means driven by said motor for rotating said turntable.
- 30 6. In combination with a vessel having a stern portion provided in the bottom thereof with an arcuate slot, a combined propelling and steering mechanism comprising a turntable mounted in said stern portion concentrically with said slot and rotatable in a horizontal plane, a pair of pivot pins rotatably journaled at transversely spaced points in the peripheral portion of said turntable and projecting downwardly through said slot, a pair of flexible propelling blades secured to and extending rearwardly from lower end portions of the respective pivot pins, a pair of cranks secured to upper end portions of the respective pins, a motor mounted on said turntable for rotation therewith and including a horizontal drive shaft extending rearwardly into the space between said pins, a pair of opposing eccentrics secured to said drive shaft and operatively connected to the respective cranks whereby said blades may be oscillated simultaneously in opposite directions, and means driven by said motor for rotating said turntable.
- 35 7. In combination with a vessel having a stern portion provided in the bottom thereof with an arcuate slot, a combined propelling and steering mechanism comprising a turntable mounted in said stern portion concentrically with said slot and rotatable in a horizontal plane, a pair of pivot pins rotatably journaled at transversely spaced points in the peripheral portion of said turntable and projecting downwardly through said slot, a pair of flexible propelling blades secured to and extending rearwardly from lower end portions of the respective pivot pins, a pair of cranks secured to upper end portions of the respective pins, a motor mounted on said turntable for rotation therewith and including a horizontal drive shaft extending rearwardly into the space between said pins, a pair of opposing eccentrics secured to said drive shaft and operatively connected to the respective cranks whereby said blades may be oscillated simultaneously in opposite directions, and means driven by said motor for rotating said turntable.
- 40 8. In combination with a vessel having a stern portion provided in the bottom thereof with an arcuate slot, a combined propelling and steering mechanism comprising a turntable mounted in said stern portion concentrically with said slot and rotatable in a horizontal plane, a pair of pivot pins rotatably journaled at transversely spaced points in the peripheral portion of said turntable and projecting downwardly through said slot, a pair of flexible propelling blades secured to and extending rearwardly from lower end portions of the respective pivot pins, a pair of cranks secured to upper end portions of the respective pins, a motor mounted on said turntable for rotation therewith and including a horizontal drive shaft extending rearwardly into the space between said pins, a pair of opposing eccentrics secured to said drive shaft and operatively connected to the respective cranks whereby said blades may be oscillated simultaneously in opposite directions, and means driven by said motor for rotating said turntable.
- 45 9. In combination with a vessel having a stern portion provided in the bottom thereof with an arcuate slot, a combined propelling and steering mechanism comprising a turntable mounted in said stern portion concentrically with said slot and rotatable in a horizontal plane, a pair of pivot pins rotatably journaled at transversely spaced points in the peripheral portion of said turntable and projecting downwardly through said slot, a pair of flexible propelling blades secured to and extending rearwardly from lower end portions of the respective pivot pins, a pair of cranks secured to upper end portions of the respective pins, a motor mounted on said turntable for rotation therewith and including a horizontal drive shaft extending rearwardly into the space between said pins, a pair of opposing eccentrics secured to said drive shaft and operatively connected to the respective cranks whereby said blades may be oscillated simultaneously in opposite directions, and means driven by said motor for rotating said turntable.
